UNITED STATES PATENT OFFICE.

CLAUDE REES, OF SAN FRANCISCO, CALIFORNIA, ASSIGNOR TO REES BLOW PIPE MANUFACTURING COMPANY, OF SAN FRANCISCO, CALIFORNIA, A CORPORATION OF CALIFORNIA.

DRYING APPARATUS.

1,413,135.

Specification of Letters Patent. Patented Apr. 18, 1922.

Application filed January 15, 1920. Serial No. 351,538.

To all whom it may concern:

Be it known that I, CLAUDE REES, a citizen of the United States, and a resident of the city and county of San Francisco and State 5 of California, have invented a new and useful Drying Apparatus, a portion of the wall being sectioned in a plane to show the air inlet, of which the following is a specification.

10 My invention relates to devices for drying fruit and other products.

An object of the invention is to provide a drier giving a dried product of even moisture content.

15 Another object of the invention is to provide a drier in which a continuous succession of fruit or other material may be economically dried.

The invention possesses other features of 20 advantage, some of which, with the foregoing, will be set forth in the following description of the preferred form of my invention which is illustrated in the drawings accompanying and forming part of the specification. It is to be understood that I do not 25 limit myself to the showing made by the said drawings and description, as I may adopt variations of the preferred form within the scope of my invention as set forth in the 30 claims.

In the drawings, Figure 1 is a horizontal section. Figure 2 is a vertical sectional view, the plane of section being indicated by the line 2—2 of Figure 1. Figure 3 is a vertical sectional view of a portion of the drier, the plane of section being indicated by the line 3—3 of Figure 2. Figure 4 is a plan view of the truck on which the trays are piled in two tiers. Figure 5 is a side elevation 40 of the truck loaded with trays.

In terms of broad inclusion the drier of my invention comprises a drying chamber through which a succession of trays containing the material to be dried is passed. Means 45 is provided for heating air and circulating the heated air about the trays, the mass of heated, moisture-absorbing air progressing in a substantially helical path passing through the trays, from the tray exit to the 50 tray entrance, where it passes out of the apparatus. Thus the entering material is subjected to warm air laden with moisture accumulated from the material ahead. If the moisture content of the entering fruit is 55 heavy, evaporation begins. If portions of

the material are already partially dry, the evaporation of such portions does not begin at this point, and there may be at first even a slight absorption of moisture by the material from the warm moist air currents. As 60 the material progresses through the heating chamber, the air currents are drier and warmer, until at the end, the material is subjected to currents of fresh air heated to the point required to bring the material to the 65 desired condition prior to discharge. Thus material of varying degrees of moisture content may be treated, the drying out of the drier portions being delayed and all of the material being brought prior to discharge 70 to the same moisture content. This results in a product of uniform character and makes it unnecessary to segregate lots of the material for separate treatment where the material initially presents different degrees of 75 dryness. The apparatus also includes means for transporting the trays through the drying chamber, and control means for directing the air currents in a substantially helical path through the laden trays. 80

Considered in detail, my drier comprises a housing 2 enclosing a long drying chamber 3 extending longitudinally therethrough, and with an entrance door 4 and an exit door 5 closing the opposite ends. 85 Rails 6 are provided upon which trucks 7 are adapted to run through the chamber. Each of the trucks is adapted to be loaded with two tiers of trays 8, the trays extending nearly to the ceiling 9 90 of the drying chamber and extending from side to side, leaving only space about them sufficient to clear the walls, as best shown in Figure 2. The laden trucks are rolled into the drying chamber one 95 after the other and are closely spaced therein. The trays are so formed and piled on the trucks and the position of the tiers of stacked trays in the drying chamber, and the construction of the drying chamber 100 are such that heated air may be passed through the tiers of trays only from side to side of the heating chamber. To this end the trays are made with end pieces, 11, Figure 5, narrower than the long side pieces, 105 so that when the trays are stacked in tiers a passage 12 is formed between the material in one tray and the bottom of the next tray above. As shown in Figures 3 and 5, the tiers on each truck are set close to- 110

gether so that no passage is provided between the tiers. In order to block any passage between the adjacent tiers on adjacent trucks, a flanged panel 13 is disposed between such tiers as the trucks are run into the chamber. These panels are formed with a longitudinally disposed flange 14 extending between the adjacent tiers to prevent the panel from being displaced, and a transverse flange 16 at the top hooking over the top trays and pentially supporting the panel. The passage under the trays and around the trucks is blocked by a pivotally arranged panel 17 extending longitudinally through the chamber and adapted to extend from the floor close to the ends of the bottom trays. Thus, except for a certain amount of leakage which is desired, the heated air introduced to one side of the heating chamber, that is to say, to one end of each of the laden trays, must flow through the passages 12 and over the material in the trays to reach the other side; that is, the movement of the air through the tiers is transversely of the drying chamber. Arranged within the housing and extending along one side of the drying chamber are heating chambers 19 and 20 separated by the wall 22. Heating devices 23 and 24 are arranged in the heating chambers and are supplied with hot gases and products of combustion from a furnace 26 disposed between the heating devices, and connected thereto by conduit 27. Each heater consists of a series of tubes 28 at each end, each series connected at the bottom into a header 29 into which the conduit 27 discharges. At the top the tubes are connected into a header 31 extending across the top of the heater and into which a second series of tubes 32 is connected on each side of the stack 33. The stack extends through the heater and at the lower end is connected into a header, lying between headers 29 and into which the lower ends of each series 32 is connected.

Reference is made to co-pending application #408,703, filed September 7, 1920, for a complete disclosure of the type of heater here referred to and not claimed.

The hot gases and products of combustion from the furnace thus pass through the conduits 27, upwardly through tubes 28 downwardly through tubes 32 and upwardly in the stack, the lower ends of series 28-32 separated by a partition not shown heating the tubes and stack. The ceiling 9 of the drying chamber is extended in the wall 34, so that air emerging from the tiers of trays, as shown by the arrows in Figure 2, necessarily passes between and around the heated tubes, and absorbs heat therefrom. The chamber 20 is closed to outside air, but chamber 19 is provided with an air inlet adjustable by the door 36, and

fresh air is drawn constantly through this inlet to compensate for the moisture laden air discharged from the housing.

Above the heating and drying chambers a space is left between the walls 9—34 and the roof 37 of the housing. Above the drying chamber this space is divided into a plurality of passages 38 by the vertical walls 39. At one end (left of Figure 2) these passages open into the upper part of the heating chambers and at the other end they open into the upper part of a passage 41, extending along the drying chamber on the side opposite to the heating chambers. Alined with the walls 39 are doors 42 in the passage 41. Closure of these doors prevents air currents moving lengthwise through the passage, and divides the passage into a number of chambers 43 opening on the inside into the heating chamber and at the top into the passages 38. Thus a complete circuit is formed for the flowing of air through the drying and heating chambers, then up and through the passages 38, downwardly into the chambers 43 and again through the trays in the drying chamber. If the doors 42 were closed, the air would continue to circulate in this manner indefinitely except for slight leakage. However under usual conditions it is desired that the air shall also progress from one end of the apparatus to the other while it is circulating in the path just noted and so the doors 42 are adjusted to permit the flowing of air therethrough, so that a portion of the mass of air may be continuously diverted to pass through the next series of passages around and through the trays in the drying chamber. The doors are therefore means for varying the speed at which the mass of air moves longitudinally through the drying chamber relative to its speed transversely through the tiers, or expressed in another way, they are the means for varying the number of turns in the helical path in which the air moves through the drying chamber, whereby the number of times which a given mass of air passes over the same lot of drying material is readily controlled.

Means are provided for mechanically inducing the flow of air currents in the passages described. In each passage 38, a fan 44 is fixed on the shaft 46 supported in suitable bearings 47. The ends of the shafts project through the housing and carry on their ends crown face pulleys 48 upon which belts 49 are arranged. At one end of the housing a line shaft 51 is journaled, and arranged to be driven by the motor 52. The other end of the line shaft is equipped with a wide, straight face tight pulley 53. The adjacent fan shaft 46^a is provided with a crown face pulley 48 for the belt 49. Next to it are closely spaced a tight crown face pulley 54, a loose crown face pulley 56 and

a tight crown face pulley 57 in the order named. An open belt 58 and a cross belt 59 connect the pulley 58 to the pulleys 54 and 56 or 56 and 57, and the usual belt shifting means is provided for shifting the belts 58 and 59 so that the fans 44 may be run in either direction. In order to facilitate the even drying of material, I find it expedient to reverse the fans and the direction of flow 10 of the air currents from time to time.

In order to insure the forward progress of the air currents, I provide a suction fan 61 driven by belt 62 from the line shaft and arranged to draw air from the end of the 15 housing adjacent the truck entrance. Thus under the influence of the fans 44 and the fan 61, and with the doors 42 adjusted in an open position, the air, with constant accretions of fresh air through the aperture controlled by the door 36, circulates in a substantially helical path, around and around through the passages and through the trays once on each complete circuit, meanwhile 20 advancing slowly longitudinally of the drying chamber from the truck discharge end of the housing toward the truck entrance, receiving a secondary heating as it passes through the heating chamber 20 and finally discharging into the open air through the 25 fan 61. From time to time the direction of motion of the air currents transversely through the trays and passages 38 is reversed, but in either direction the action of the fan 61 induces the forward progression 30 or longitudinal movement of the air as it accumulates moisture from the drying material.

While any suitable truck will do, I prefer to use one made as shown in Figures 4 and 40 5 and comprising wheels 63 joined by an axle 64 at each end. Frame members 66 are underslung upon the axles and transverse members 67 are secured to them, blocks 68 being provided on which the lowermost 45 trays of the tiers rest closely adjacent to the wheels.

I claim:

1. A drying apparatus comprising a drying chamber, heating chambers along one 50 side of the drying chambers, a passage along the opposite side of said chambers, a ceiling covering the drying chamber and forming a reverse air space connecting the heating chambers and the said passage, tiers of supports for material which is arranged to form superposed, spaced layers, and means for causing heated air to circulate in a helical path and along the spaces between the said layers.

60 2. A drying apparatus comprising a drying chamber, means for regulating the inlet of air, means for creating a substantially helical current of air traversing said drying chamber and progressing longitudinally 65 therethrough, means for heating said air

current, and means arranged within the chamber for varying the speed at which said current progresses longitudinally through said drying chamber relative to its transverse speed.

3. A drying apparatus comprising a drying chamber, means for creating a substantially helical current of air traversing said drying chamber once in each complete turn of the helix and progressing longitudinally 70 therethrough, means for heating said air current, means for regulating the inlet of air, means for varying the number of turns in the helical path in which said air current flows, and trays forming spaces between 75 which the air passes horizontally.

4. A drying apparatus comprising a drying chamber, in which are arranged trays forming horizontal passages, means for creating a substantially helical current of air 80 traversing said drying chamber through said passages once in each complete turn of the helix and progressing longitudinally therethrough, means for heating said air current, means for controlling the inlet of 85 air, means for varying the speed at which said current progresses longitudinally through said drying chamber relative to its transverse speed.

5. A drying apparatus comprising a drying chamber, means for creating a substantially helical current of air traversing said drying chamber once in each complete turn of the helix and progressing longitudinally therethrough, means for heating said air 90 current, means for varying the speed at which said current progresses longitudinally through said drying chamber relative to its transverse speed, means for passing a succession of material to be dried through said 95 chamber, and means for reversing the direction of movement of said current transversely through said chamber.

6. A drying apparatus comprising a drying chamber, means for creating a substantially helical current of air traversing said drying chamber once in each complete turn of the helix, means for varying the number of turns in the helical path in which said air current flows, means for maintaining said 110 air current at substantially an even temperature, means for providing constant accretions of fresh air to said current, compactly arranged trays in said chamber, and means for directing the air horizontally between the trays.

7. A drying apparatus comprising a drying chamber, means for creating a substantially helical current of air traversing said drying chamber once in each complete turn 115 of the helix and progressing longitudinally therethrough, means for heating said air current, means for varying the speed at which said current progresses longitudinally through said drying chamber relative to its 120

130

transverse speed and means for reversing the direction of movement of said current transversely through said drying chamber.

8. A drying apparatus comprising a drying chamber, means for creating a substantially helical current of air traversing said drying chamber once in each complete turn of the helix and progressing longitudinally therethrough, means for heating said air current, means for varying the speed at which said current progresses longitudinally through said drying chamber relative to its transverse speed, means for reversing the direction of movement of said current transversely through said drying chamber, and means for passing a succession of material to be dried through said drying chamber.

9. A drying apparatus comprising a drying chamber, tiers of trays in said chamber for the material to be dried and arranged with a passage above the material on each tray extending through the tiers transversely only of said chamber, the trays arranged in close juxtaposition to prevent by-pass of air, means for flowing a mass of heated air transversely across said drying chamber and substantially wholly through said passages, and means for permitting the gradual progression of said mass of air longitudinally through said drying chamber.

10. A drying apparatus comprising a central drying chamber, a longitudinal row of tiers of supports in said chamber for the material to be dried and arranged with a horizontal passage above layers of the material in each tier extending through the tiers transversely only of said chamber, means for flowing a mass of heated air transversely across said drying chamber and through said passages, means for permitting the gradual progression of said mass of air longitudinally through said drying chamber, and a lateral tunnel along the drying chamber.

11. A drying apparatus comprising a dry-

ing chamber, tiers of trays in said chamber for the material to be dried and arranged with a passage above the material on each tray extending through the tiers transversely only of said chamber, means for flowing a mass of heated air transversely across said drying chamber and through said passages, means for permitting the gradual progression of said mass of air longitudinally through said drying chamber, means for conveying a succession of tiers of trays through said chamber, and means for reversing the direction of movement of said mass of air transversely through said passages.

12. A drying apparatus comprising a drying chamber, tiers of trays in said chamber for the material to be dried and arranged with a passage above the material on each tray extending through the tiers transversely only of said chamber, trucks for conveying a succession of tiers of trays through said chamber, heating chambers opening upon the side of said drying chamber and the passages through said tiers, a plurality of passages communicating with said heating chambers and opening upon the opposite side of said drying chamber and the opposite ends of the passages through said tiers, a fan in each of said communicating passages for inducing a current of air through said tiers, heating chamber and communicating passages, means for driving said fans in either direction, means for controlling the leakage of air currents between the successive tiers and below the trucks, and means for causing a gradual progression of the mass of air in said air currents longitudinally through said drying chamber and the succession of tiers of trays therein.

In testimony whereof, I have hereunto set my hand at San Francisco, California, this 8th day of January, 1920.

CLAUDE REES.
